Stanley M. Kildall,
ATTORNEY.

UNITED STATES PATENT OFFICE.

DE FOREST W. CANDLER, OF DETROIT, MICHIGAN, ASSIGNOR TO GEORGE M. HOLLEY, OF DETROIT, MICHIGAN.

CASTING OF IRON IN PERMANENT IRON MOLDS.

Application filed March 16, 1922. Serial No. 544,114.

To all whom it may concern:

Be it known that I, DE FOREST W. CANDLER, a citizen of the United States, residing at 2932 West Grand Boulevard, Detroit, in the county of Wayne and State of Michigan, have invented certain new and useful improvements in the Casting of Iron in Permanent Iron Molds, of which the following is a specification.

10 My invention relates to the casting of iron in permanent iron molds, and relates specifically to the provision of a sand core in conjunction with the sprue and gate.

Figure I shows in elevation the face of a mold with the core in position. Figure II shows a sectional plan view of the two halves of the mold when closed and ready for pouring. Figure III shows in plan view the mold.

20 In Fig. I, A is the sprue, B is the gate, C is the core, D is the annular clearance between the core C and the mold, E is the matrix, F is the core for the matrix E where the casting requires such a core, G 25 is the core print supporting the core F.

The space D around the dry sand core C is arranged eccentrically with relation to C so that the iron entering at A, flowing through the restricted passage B is distributed around the core C so as to give a substantially uniform flow into the matrix E, around the core F. That is to say the metal flows into the matrix on the side adjacent to the gate B and also through a diminishing annulus around the core C into the matrix E.

Fig. II shows a section through the mold on the planes X—Y and W—Z.

The advantage of this arrangement is that not only are any impurities in the iron held back by the restriction B, but what is much more important is that the iron as it enters first strikes the sand core B, which being porous, provides a vent for any gases occluded in the iron, the gases escaping through H.

By this arrangement the castings are much more uniform than castings obtained when the iron enters through a sprue placed in the normal location as shown on the dotted lines to the left of Fig. I, marked A'.

In molds in which a core F is not re-

quired, the dry sand core C is used nevertheless, as its function is independent of the core F. The thin annular rim cast in the annular space D is easily broken off and the fractured surface is easily machined.

What I claim is:

1. In combination with a permanent iron mold for the die-casting of iron of a substantially vertical sprue and a substantially horizontal gate of restricted area both located within the mold, a substantially vertical dry sand core against which the molten iron is delivered laterally, a descending passage for the iron from the gate past the core into the matrix of the mold.

2. In combination with a permanent metal mold for the die-casting of iron a substantially vertical sprue having a substantially horizontal gate of restricted area both located within the mold, a dry sand core interposed between the gate and the matrix of the mold, located above the matrix and arranged so that the molten metal is delivered laterally against the surface of the core before entering the matrix of the mold, whereby the core can act as a vent to the molten metal as it issues from the gate.

3. In combination with a permanent metal mold for the die-casting of iron a substantially vertical sprue leading to a substantially horizontal gate of restricted area both located within the mold, a dry sand core interposed between the gate and the matrix of the mold, located above the matrix and arranged so that the iron is delivered laterally against said core and a vent for the said core, a passage arranged on one side of said core leading to the matrix of said mold.

4. In combination with a permanent metal mold for die-casting iron, a substantially vertical sprue having a substantially horizontal gate of restricted area both located within the mold, a cylindrical dry sand core interposed between the gate and the matrix of the mold, located above the matrix and arranged vertically and eccentrically within the matrix so as to give a substantially vertical passage on the side of the core adjacent to the gate leading downwardly to the matrix.

5. In combination with a permanent iron mold for the die-casting of iron, a sprue with an entrance having a substantially vertical axis, said sprue leading to a restricted gate, said gate being located laterally with reference to said axis, a dry sand core located between the restricted gate

and the matrix of the mold, a passage along the core leading to the matrix of the mold.

10

In testimony whereof I affix my signature.

DE FOREST W. CANDLER.
